[57] CLAIM

The ornamental design for an upholstered chair, as shown and described.

DESCRIPTION

FIG. 1 is a front perspective view taken from the left side of an upholstered chair showing my new design; FIG. 2 is a side perspective view;

FIG. 3 is a rear perspective view taken from the left side;

FIG. 4 is a front perspective view;

FIG. 5 is a rear perspective view.

The design is characterized by the ornamental seat and backrest cushions and the essentially right-angled side arm members in combination with the bridging transverse trim element disposed between the seat and backrest cushions, all as best illustrated in FIGS. 2 and 3.

FIG. 1

FIG. 2

FIG. 3

FIG. 4

FIG. 5
